SWEETENING PROCESS

Albert J. Brandel, Compton, Calif., assignor to
 California Research Corporation, San Francisco, Calif., a corporation of Delaware

Application July 23, 1949, Serial No. 106,420

5 Claims. (Cl. 196—24)

1

This invention relates to an improvement in lead sulfide sweetening of petroleum distillates.

The lead sulfide sweetening process has been in commercial use in the United States for a number of years. In the practice of the process, a petroleum distillate is intimately contacted with an aqueous caustic treating solution containing insoluble lead sulfide in suspension. The aqueous solution of alkali preferably comprises a 20 to 30° Bé. caustic soda solution, although as low a concentration as 1° Bé. is operative. The more dilute caustic solutions give slower sweetening reaction rates. The amount of lead sulfide in suspension in the caustic solution may vary from $\frac{1}{10}$ to 2 pounds of lead sulfide per gallon of reagent. The preferred proportions are from 0.5 to 1 pound of lead sulfide per gallon. Alkali hydroxides other than sodium hydroxide, for example, potassium hydroxide, may be used in the aqueous portion of the treating agent. Additional ingredients such as agents which reduce the interfacial tension between oil and water may also be present in the treating agent. The sodium salts of phenols or other acidic bodies present in petroleum are examples of such interfacial tension-reducing agents.

In the practice of the process, a hydrocarbon distillate containing mercaptans is contacted with the lead sulfide-caustic treating agent in the presence of added air or oxygen. The amount of air is controlled according to the mercaptan content in order to keep the treating reagent in a "balanced" condition, one-fourth mol of oxygen being required for each mol of mercaptan sulfur contained in the distillate. The mechanism by which the lead sulfide sweetening process effects the sweetening of petroleum distillates is thought to follow the pattern set out in the following equations:

The treating solution is in a "balanced" condition when substantially all of the lead is present in the form of lead sulfide, the amount of water-soluble lead compounds being ordinarily 0.003 pound of lead per gallon of reagent or less, and when only traces of soluble sulfides are present in the reagent. The mechanism of the sweetening process as indicated by the above equations requires that oxygen be contacted with the treating agent in amount sufficient to produce the sulfur necessary for reaction with lead

2

mercaptides to produce disulfides and return the lead to the form of lead sulfide. Balance is maintained by adjusting the rate at which air is introduced in accordance with the mercaptan content of the feed and by introducing sodium sulfide as required to insure the necessary low content of water-soluble lead compounds. This process has been described in some detail in U. S. Patent 2,208,591.

In the commercial practice of the lead sulfide sweetening process, the formation of emulsions has frequently presented serious operating problems. When the feed and the treating agent form emulsions, the sweetening time is lengthened, lead sulfide is carried out of the treating plant with the finished product, and a drop of 5 to 7 numbers on the Saybolt color scale may be shown by the finished product. In the past, it has been the practice to meet the emulsion problem by reducing the feed rate to the lead sulfide treating plant. The reduction of feed rate ordinarily reduced or eliminated the emulsion difficulties, but obviously had an adverse effect on the throughput of the plant. On occasions the emulsion problem has become so severe that it has been necessary to pump the entire batch of emulsified treating reagent out of the plant into a storage tank, where it was subjected to a prolonged settling period, while a fresh charge of treating reagent was introduced into the plant. Neither of these methods provided an entirely satisfactory solution to the problem of emulsion formation.

It now has been found that the formation of emulsions during the lead sulfide sweetening process may be substantially completely eliminated and that the feed rate and mercaptan tolerance in the feed can be increased by maintaining in solution in the treating agent a minor proportion, ordinarily between about 0.3% and 3% of sodium sulfonates prepared by sulfonating a fraction of the sulfur dioxide extract of kerosene and preferably recycling a sufficient portion of the sweetened product to the treater to reduce the mercaptan sulfur content of the mixture of fresh feed and sweetened product entering the treater to below about 0.02% by weight. The fraction of the extract which is sulfonated has a boiling range between about 400 and 530° F. The resultant sulfonic acids are then neutralized with caustic soda.

The invention may be more completely understood by reference to the drawing, which is a diagrammatic illustration of the apparatus and process flow employed in the practice of this in-

vention. Sodium hydroxide is introduced into mixing tank 3 via lines 1 and 2. Lead oxide is introduced into tank 3 through inlet line 4 and the sodium sulfonates referred to above, and more particularly described hereinafter, are introduced into mixing tank 3 through line 5. The resulting mixture of doctor solution and sodium sulfonates is withdrawn from tank 3 through line 6 and is pumped into line 7. Sodium sulfide is introduced into tank 10 via line 8 and water is introduced into tank 10 via line 9 to prepare a sodium sulfide solution. This solution is withdrawn from tank 10 through line 11 and passed via line 12 into blowcase 13. Air is introduced into line 14 and is passed into blowcase 13 to expel the sodium sulfide solution from the blowcase through line 15 into line 7. Feed is introduced into line 16 and the feed from line 16 and the treating reagent, now consisting of sodium sulfide suspended in caustic, are drawn into pump 17, where they are intimately mixed and forced through line 18 and loopy mixer 19 into treater 20. Air is passed from line 14 through line 21 into line 18 in amount necessary to keep the solution in balance. The mixture of feed and treating agent has a short residence period in treater 20, where a partial phase separation is effected. The overflow from treater 20 consisting of feed and treating agent, flows through line 22 into inclined settler 23, where the phase separation between the feed and treating agent becomes substantially complete. The treated distillate is withdrawn from settler 23 through line 24 and is passed through a rock-packed coagulator 25, where any minor proportions of lead sulfide which may remain suspended in the product are removed. The sweetened feed is withdrawn from coagulator 25 through line 26 as the process product. Treating agent settling out of the mixture of feed and treating agent in treater 20, in settler 23, and in coagulator 25 is withdrawn from these vessels via lines 27, 28, and 29, respectively, and passed through reagent recirculation line 30 into line 7. Lines 31, 32, and 33 are illustrative of the provision made for handling liquid withdrawn from coagulator 25, settler 23, and treater 20, respectively. Each of these vessels is provided with a series of try cocks from which liquid level may be determined and from which samples may be withdrawn. The liquids so withdrawn pass through line 34 into drip sump 35, from which this material may be either withdrawn from the system via line 36, returned to treater 20 via lines 7 and 18, or introduced into mixing tank 3 via lines 37 and 2. Line 39 is provided for the return of a portion of the sweetened distillate to line 16 to dilute the feed and reduce the mercaptan content of the oil entering pump 17 to below 0.02% by weight calculated as mercaptan sulfur. This line may also be used to return off-test product to the system for further treatment. Line 38 is provided to permit passage of sodium sulfide solution directly into line 22 and thence into settler 23 as required.

The difficulties caused by the emulsions encountered prior to the employment of sodium sulfonates as a component of the treating reagent will be readily appreciated to be serious upon inspection of the flow diagram set out in the drawing.

The efficiency of the particular sodium sulfonates referred to above and described in detail hereinafter to eliminate the emulsion problem and to increase sweetening capacity was tested in a commercial lead sulfide treating plant processing 4000 barrels per day of a pentane-hexane

cut of thermally cracked naphtha. The sodium sulfonates were added to the treating agent in amount sufficient to constitute 1% of the reagent volume. After this addition the feed rate to the treating plant was increased from a previous maximum of about 4000 B./D., at which rate sweetening was sometimes incomplete and reagent losses were high, to 10,000 B./D., at which rate the treating stock passed doctor and color tests and the reagent separation was excellent. During the run the mercaptan sulfur content of the feed was increased from 0.015% to 0.04% without encountering any resultant treating or operating difficulties, although stocks of higher mercaptan content are normally more difficult to sweeten and emulsify more readily with the treating reagent. The employment of this reagent was continued in a commercial scale unit for a period of three months during which an average feed rate of 6000 B./D. was maintained and during which entirely satisfactory sweetening was obtained without encountering any emulsion formation.

The sodium sulfonates which are employed in the process of this invention are prepared by the following process. Kerosene is extracted with sulfur dioxide. The extract is distilled and an approximately 60% to 90% cut of the extract is taken overhead. The overhead has an initial boiling point of about 400° F. and an end point not above 530° F. on an ASTM-D-86 distillation. This distillate is sulfonated by mixing about 10 volumes of the distillate with approximately 6 volumes of a low viscosity oil such as a heavy kerosene or a spray oil having a viscosity of about 300 Saybolt seconds at 210° F. that is inert to 98% sulfuric acid. The oil is added to absorb some of the heat of reaction and a properly designed heat exchanger or cooling coil may be used to control temperature, in which case the oil addition may be eliminated. Eight volumes of 95-98% sulfuric acid are slowly added to the mixture of distillate and low viscosity oil with agitation over a period of about an hour. Cooling, or the addition of further low viscosity oil, is resorted to to maintain the temperature within the approximate limits of 120° to 130° F. When the sulfonation is complete, about 15 volume per cent of water is added to the reaction mixture and the resulting mixture is agitated for a short period. After a settling time of 5 to 20 minutes, the lower weak acid layer is drawn off. The sulfonic acid is then neutralized with 33° Bé caustic to a pH of 8 to 10. After 4 to 5 hours, the unsaponifiable oil separates as an upper oily phase, and a lower aqueous phase containing sulfonates and sulfate is transferred to a cooling tank and cooled to 65° to 70° F. At this temperature, sodium sulfate crystallizes from the solution and a clear solution of the desired sodium sulfonates is obtained by decantation. If lower gravity caustic is used in neutralizing the sulfonic acid, the final concentration of sulfonates will be lower.

The kerosene subjected to SO₂ extraction in the initial step may be obtained from any of the crude oils now refined in large volume in this country. Kerosenes from waxy crudes are ordinarily used and the sulfonates prepared from them are preferred. The SO₂ extraction is ordinarily conducted at temperatures below 50° F. and the volume of SO₂ per volume of oil is in the range 0.25 to 1.0. It is the aromatic materials extractable by SO₂ which are desired for sulfonation and, while SO₂ is the preferred sol-

vent, other solvents such as hydrofluoric acid, furfural, phenol, and acetonitrile yield extracts which may be processed as above described to produce the desired sulfonates. The sulfonates may be prepared by treating a suitable kerosene fraction with sulfuric acid, omitting the extraction step; however, it is preferred to employ the extract as the starting material.

The sodium sulfonate product has the following properties: It is a brown, free-pouring liquid which is miscible in all proportions with water and insoluble in hydrocarbons. It is an alkyl-aryl type sodium sulfonate with surface active properties.

Typical tests (content by weight)

Sodium sulfonates	52.0% by weight.
Water	45.5% by weight.
Inorganic salts	2.5% by weight.
Water insoluble	0.10% by weight.
pH of 5% in water	9.
Appearance	Clear, brown liquid.
Specific gravity	1.203.
Lbs. per gallon	10.0.
Molecular weight of sodium sulfonates	270 (approx.).
Gardner viscosity, 25° C.	0.4 poise.

As indicated previously, the sodium sulfonates are added to the lead sulfide treating agent in amounts between 0.3 and 3% by volume. This is on the basis of volumes of the aqueous sodium sulfonate solution described in the above table per volume of lead sulfide treating reagent. On a weight basis the amount of sulfonates added to the lead sulfide reagent is between about 0.15 and 1.5%. Amounts lower than 0.15% by weight do not effectively prevent emulsion formation and amounts appreciably in excess of 1.5% by weight have been found in some cases to aggravate rather than reduce emulsion difficulties.

The discovery that the particular sulfonate composition described above was effective in preventing the formation of emulsions during the lead sulfide treating process was made after a prolonged study of the emulsions formed and a correspondingly long experimental program in which a great many reagents, including a number of other sodium sulfonates, were tested in unsuccessful attempts to break the emulsions. No other reagent has been found which is effective for this purpose. A variety of commercially available emulsion-breakers, including a number of reagents sold under the trade name "Tret-O-Lite," were tested without obtaining any beneficial result. Sodium sulfonates prepared by the sulfonation of other petroleum fractions and sulfur dioxide and phenol extracts of other petroleum fractions were ineffective in breaking the emulsions formed in the lead sulfide sweetening process. Various sulfonates prepared for use as commercial detergents, such as alkyl aryl sulfonates, were ineffective for this purpose.

The mechanism of the reaction by which the sodium sulfonates above described improve both the reagent separation and the sweetening characteristics of the reagent is not understood, but the results obtained show a marked and valuable improvement in the efficiency of the process.

I claim:

1. In the lead sulfide sweetening process, the improvement which comprises maintaining in solution in the lead sulfide treating agent a minor proportion, sufficient to inhibit emulsion

formation in the process, of sodium sulfonates prepared by sulfonating a fraction of a sulfur dioxide extract of kerosene boiling in the range of about 400-530° F. and neutralizing the sulfonated product with caustic soda.

2. In a process for sweetening petroleum distillates comprising agitating the oil and air with a treating agent comprising a suspension of lead sulfide in an aqueous solution of an alkali metal hydroxide, the improvement which comprises maintaining in solution in the alkali metal hydroxide solution a minor proportion, sufficient to inhibit the formation of emulsions of the oil and treating agent, of sodium sulfonates prepared by sulfonating a fraction of a sulfur dioxide extract of kerosene, said fraction having a boiling range about 400-530° F., and neutralizing the resultant sulfonic acids with caustic soda.

3. In a process for sweetening gasolines and kerosenes comprising agitating the oil and air with a suspension of lead sulfide in caustic soda solution, the improvement which comprises maintaining in solution in the caustic soda solution a minor proportion not less than about 0.15% by weight of sodium sulfonates prepared by sulfonating a fraction of a sulfur dioxide extract of kerosene, said fraction having a boiling range of about 400-530° F. and neutralizing the resultant sulfonic acid with caustic soda.

4. In a process for sweetening mercaptan-containing petroleum distillates comprising agitating the distillates in a treating zone with a treating agent comprising lead sulfide suspended in an aqueous sodium hydroxide solution, the improved method which comprises recirculating a sufficient amount of the sweetened product to the treating zone to reduce the mercaptan sulfur content of the total oil entering said zone to below 0.02% by weight, and maintaining in solution in the treating agent between about 0.15 and 1.5% by weight of sodium sulfonates prepared by extracting kerosene with sulfur dioxide, separating a fraction of the extract boiling in the range about 400° F. to 530° F., sulfonating said fraction by treating it with concentrated sulfuric acid at a temperature in the range about 120° F. to 130° F., and neutralizing the sulfonated product with caustic soda.

5. In a process for sweetening mercaptan-containing petroleum distillates which comprises agitating the oil and a treating agent comprising lead sulfide suspended in aqueous sodium hydroxide in a treating zone, the improved method which comprises maintaining in solution in the treating agent a minor proportion, sufficient to inhibit the formation of emulsions, of sodium sulfonates prepared by the steps comprising sulfonating a fraction of an SO₂ extract of kerosene boiling in the range about 400° F. to 530° F. with concentrated sulfuric acid at a temperature in the range about 120° to 130° F., separating the resulting sulfonic acids and neutralizing them with concentrated sodium hydroxide, separating the unsaponified oil from the aqueous phase containing sodium sulfonates, cooling the aqueous phase to 65°-70° F. to crystallize sodium sulfate, and decanting an aqueous sodium sulfonate solution.
